CEMENTING HOOK

Harold L. Strader, Houston, Tex., assignor to
 Hughes Tool Company, Houston, Tex., a corporation of Delaware

Application April 5, 1940, Serial No. 327,933

5 Claims. (Cl. 255—25)

This invention relates to apparatus employed in the cementing of casing in wells.

When casing has been properly set in a well and the cementing of the casing is being performed, it is desirable to move the casing so that the cement may be circulated about it to assure that the cement thoroughly fills the space outside the casing at the lower end thereof. The equipment for circulating the cement into the hole includes, in the usual arrangement, a cement conducting line running directly from the pump to a closure cap at the upper end of the casing. With such an installation the casing cannot be rotated or raised or lowered during the operation of circulating the cement into position. Thus the operator must rely upon heavy fluid pressure exerted upon the cement to try and force it into position and also upon expensive forms of cement shoes on the casing. Often without complete success.

It is an object of my invention to provide an apparatus whereby the casing may be moved as desired while the cementing job is being performed. I desire to allow rotary movement of the casing and also vertical reciprocation, so that the cement can be worked about the pipe and thus assure that the cement completely fills the lower end of the well.

I wish to so support the casing and to connect the cement pipe thereto, that the movement of the casing during cementing will not interfere with the simultaneous forcing of the cement into position.

Further objects and advantages of the invention will more clearly appear from the description which follows taken with the drawing herewith in which:

Fig. 1 is a side elevation of the supporting device which I employ in carrying out the invention.

Fig. 2 is a perspective view partly in section, showing the hook employed between the swivel and the elevators.

Fig. 3 is a vertical section showing the upper end of the casing and the cementing connections therewith.

In carrying out my invention I employ a swivel A arranged to rotatably support an elevator B, which is adapted to engage about the upper end of the casing C.

The swivel is of ordinary construction. It has a bail 1 carrying a supporting body 2 for supporting the relatively rotatable nipple 3. A goose neck 4 is provided for connection with the cementing hose not shown.

The nipple 3 is connected, at its lower end to a

cemeting hook 24 by a threaded engagement, within a socket 5 in said hook. Said hook has a passage 6 therein for the cement. A lateral threaded opening in said passage has connection with a flexible metallic hose 7. Any ordinary type of rubber or fabric hose may be used. Opposed hooks 8 are formed to be engaged by the bails 9 of the elevator B.

The elevator is of ordinary construction. It has a body 10 adapted to engage below the upper collar 11 upon the casing C. The upper end of the casing is closed by a nipple 12 screwed into the collar 11 and having a cap 13 secured thereto by means of a coarsely threaded connection 14. A lateral threaded port 15 in the nipple 12 provides attachment for the lower end of the flexible hose 7. The cap 13 has opposite upwardly extending ears 16 thereon to be engaged by a wrench or bar in screwing up or unscrewing the cap.

In the operation of cementing, fluid for cleaning the well may first be circulated from the pump through the goose neck 4, the swivel nipple 3, the cementing hook 24, the flexible hose 7, the nipple 12 into the casing and the well. Then the cement may be forced into the well by the same route. When sufficient cement has been pumped into the well, a plug may be inserted above the cement by removing the cap 13 and mud may be then employed to move the plug to the bottom in the usual manner, thus forcing the cement out of and up around the casing.

The casing may be engaged by the rotary or by pipe wrenches or other similar means and rotated as desired without interfering with the pumping of the cement into position in the well. By thus moving the casing a proper positioning of the cement in the hole and about the casing is assured. No special shoes upon the casing or other devices are necessary to assist in placing the cement. Also, during the process of washing and cementing the casing may be raised and lowered as desired by the usual hoisting mechanism connected with the swivel.

What I claim as new is:

1. A device for cementing casing in wells including a swivel, a cementing hook secured thereto, a closure member for the upper end of the casing, an elevator connected, with said hook and engaging about said casing, and a flexible cement conducting member connecting said hook and said closure member to conduct cement into said casing.

2. A device for conducting cement into wells including a swivel, a fluid conducting passage therethrough, a relatively rotatable nipple there-

- on, a cementing hook on said nipple, an elevator supported on said hook, a casing engaged by said elevator, and means to conduct fluid from said hook to said casing past said elevator.
5. A connection between a swivel and a well casing, including a hook secured to said swivel, said hook having an upper hollow shank thereon to receive fluid from said swivel, a closure means for the upper end of said casing, means on said hook to support said casing, and a flexible fluid conduit connected with said hollow shank and said closure means to conduct fluid from said swivel past said supporting means to said casing.
10. In combination a swivel, a cement hook thereon, a hollow shank on said hook to receive fluid from said swivel, a casing closed at its upper end, an elevator on said hook engaging said casing, and a fluid conducting line from said hollow shank to said casing.

4. A swivel, a well casing closed at its upper end, an elevator on said swivel engaging and supporting said casing, and a flexible fluid conducting line connecting said swivel past said elevator with the interior of said casing.

5. In combination a swivel, a cement hook thereon, a hollow shank on said hook to receive fluid from said swivel, a casing closed at its upper end, an elevator on said hook engaging said casing, and a fluid conducting line from said hollow shank to said casing.

HAROLD L. STRADER.
